201,491

BOTTLE CAP FEEDER

William E. Whitchurch, Belvidere, Ill., assignor to Champion Papers Inc., Hamilton, Ohio, a corporation of Ohio

Filed Dec. 19, 1963, Ser. No. 77,865

Term of patent 14 years

(Cl. D2—3)

FIG. 2 is a front elevational view thereof;

FIG. 3 is an elevational view of the side thereof opposite that of FIGURE 1;

FIG. 4 is a rear elevational view thereof, and

FIG. 5 is a top view thereof.

I claim:

The ornamental design for a bottle cap feeder, substantially as shown.
